[57] CLAIM

The ornamental design for a key caddy, as shown and described.

DESCRIPTION

FIG. 1 is a front elevational view of the key caddy showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an isometric view showing a use thereof;

FIG. 8 is an isometric view showing the item at a right angle thereof; and,

FIG. 9 is an isometric view showing the item at a left angle. The broken line showing of indica and keys in FIGS. 1, 2 and 7-9 are for illustrative purposes only and form no part of the claimed design.
